UNITED STATES PATENT OFFICE.

JAMES C. LYNCH, OF CHICAGO, ILLINOIS.

LOCKING MEANS FOR BUREAU-TRUNKS.

No. 874,518.

Specification of Letters Patent.

Patented Dec. 24, 1907.

Application filed November 21, 1906. Serial No. 344,416.

To all whom it may concern:

Be it known that I, JAMES C. LYNCH, a citizen of the United States, and a resident of the city of Chicago, in the county of Cook 5 and State of Illinois, have invented certain new and useful Improvements in Locking Means for Bureau-Trunks; and I do hereby declare that the following is a full, clear, and exact description of the same, reference being had to the accompanying drawings, and 10 to the letters of reference marked thereon, which form a part of this specification.

This invention relates to locking means for bureau trunks and more particularly to 15 means for securing the drawers for sliding tills in place.

It is an object of this invention to provide a positive and efficient locking means for the drawers or sliding tills adapted to rigidly en- 20 gage the same in place when the cover of the trunk is closed and adapted to be secured by the same lock which locks the lid or cover so that when said trunk is opened by raising the cover or lid the entire contents are ac- 25 cessible.

It is also an object of the invention to afford a locking device of much greater strength than has heretofore been used and capable of being instantaneously adjusted in locking 30 position so that locking the lid of the trunk also locks the trunk as a whole.

The invention consists in the matters hereinafter described and more fully pointed out and defined in the appended claims.

In the drawings: Figure 1 is a fragmentary view of a trunk embodying my invention showing the lid closed and the drawers or tills locked. Fig. 2 is a similar view with the trunk open and the tills partly extended. 40 Fig. 3 is an enlarged fragmentary vertical section taken through one of the corner bumpers of the locking bar. Fig. 4 is a similar fragmentary section taken through the corner of the cover or lid and the locking bar. 45 Fig. 5 is a plan view of the hinge embodied in my invention.

As shown in the drawings: A indicates the body of the trunk and B the lid which in the construction indicated is the usual lid of a 50 wall trunk though, of course, the invention may be applied to trunks of other kinds. Said trunk, is provided with a plurality of drawers, as shown three in number, indicated by C, C' and C² which are slideable in 55 the front of said trunk and above which and

connecting the end walls of the trunk and affording a rigid wall for the lid to close upon, is a rail or partial front wall a, on which is secured the lock E for securing the lid and within which in the top of the trunk fits the 60 usual removable till or tray a'. At the bottom of the trunk and affording a part of the front wall thereof is a bottom rail a², corresponding the top rail a.

Locking bars are hinged on each end member of the trunk and comprise angle bars D, adapted to fit around the corners and engage transversely the ends of the drawers, when closed, as shown in Fig. 1. These angle bars, as shown, are hinged on the end of the trunk 70 to afford a vertical adjustment and for this purpose a leaf d, of a hinge having a relatively long pintle d', is rigidly secured at the rear edge of each angle bar and a relatively narrow leaf d², of the hinge is rigidly secured 75 on the end of the trunk, as shown in Figs. 1 and 5, and slidably engages the pin to thus enable said bar to be adjusted vertically. The lower end of each bar, as shown, is straight and adapted to fit in a recess in the 80 top of the bottom knuckle or bumper d³. The upper end of the locking bar D has secured thereon by riveting or other suitable means, a knuckle or corner piece d⁴; flanged inwardly at its top and adapted when the 85 locking bar is seated at its lower end in the knuckle d³, to project inwardly on the top of the trunk at its corner to be firmly engaged by the closing of the lid, the corner knuckles or bumpers b of which fits down over the 90 ends thereof, as shown in Figs. 1 and 4.

The operation is as follows: In opening the trunk all that is necessary is to unlock the lid, raise the same, lift each of the locking bars from the lower knuckles or bumpers 95 and pull the drawers outwardly. Obviously any of the drawers may then be opened without disturbing any of the other drawers or necessitating the use of any other lock than that locking the lid. In closing the trunk 100 the locking bars are swung into place, dropping the lower ends into the seat in the corner bumpers, as shown in Figs. 1 and 3, in which position the flange d⁵, at the upper ends of the locking bars rests on the corner of the 105 trunk body. The lid is now closed firmly holding the locking bar in place and preventing the same lifting even though the upper or corner knuckles or bumpers on the lid should be knocked off or removed the lid 110

when locked obviously locks the entire trunk. By this construction it is obvious that if either of the locking bars be broken off, the other would rigidly secure the drawers in closed relation. It is also obvious that either of the knuckles or bumpers *a* or *b* could be broken off without permitting the drawers to open. In fact it is only possible to open the drawers after the lid is raised.

10 This is not likely to happen from the ordinary accidents of the road.

Obviously details of construction may be varied and I do not purpose limiting this application for patent otherwise than necessitated by the scope of the appended claims.

I claim as my invention:

1. In a device of the class described the combination with a trunk of a bumper rigidly engaged to each lower front corner and 20 to the lid, a locking bar, a knuckle rigidly engaged to the top thereof adapted to fit over the top of the trunk, said locking bar being vertically adjustably and its lower end seating in the lower bumper and its upper end 25 engaged beneath the lid.

2. The combination with a trunk and lid of a bumper rigidly engaged to each front corner of the lid and trunk, a vertically adjustable locking bar comprising an angle bar, 30 a knuckle rigidly engaged to the top of said bar, an integral transverse flange on said knuckle adapted to fit over the corner of the trunk and beneath the lid thereby firmly preventing vertical movement of the locking 35 bar when said trunk is locked.

3. The combination with a trunk, and slideable drawers in the front of the same, of a locking bar comprising an angle bar adapted to fit around the front edges of said drawers 40 and trunk, a leaf hinge engaged to the angle bar having a long pintle, a shorter hinge engaged to the trunk and permitting vertical adjustment of the angle bar, but preventing removal of the same, and a knuckle on the 45 top of the locking bar adapted to engage around the top corners of the trunk and beneath the lid thereof.

4. A locking bar comprising an angle bar, 50 open at the bottom, a knuckle rigidly engaged to the top adapted to engage between the lid and top of the trunk, a vertical adjustable but non-separable hinge engaged one leaf to the trunk and one to the angle bar thereby permitting vertical adjustment of 55 the locking bar and preventing the removal thereof from the trunk.

5. A locking bar of the class described embracing an angle bar having on the rear edge thereof a hinge, one leaf of which is provided 60 with long pintle, the other leaf of which is adapted to be rigidly engaged to the trunk and is relatively short, thus permitting vertical adjustment of the locking bolt to engage in recesses in the bumpers.

6. In a device of the class described, the 65 combination with a trunk of a locking bar therefor embracing an angle bar, a knuckle engaged to the upper end thereof, a recessed bottom knuckle or bumper to receive the lower end of the locking bar, an upper 70 bumper or knuckle adapted to fit over the knuckle on the locking bar, means integral with the knuckle on said bar adapted to engage beneath the lid of the trunk and prevent movement of the bar when the lid is closed 75 and means affording vertical adjustment of the angle bar.

7. In a device of the class described the combination with a trunk of a bottom corner bumper having a recess in its top, a top corner bumper, a locking bar comprising an angle bar shaped at its ends to fit in said recess and to fit beneath the top bumper and a hinge for said locking bar having one leaf engaged to the bar and one to the trunk and 80 one of said leaves having a long pintle affording relative movement between the 85 same.

8. A bureau trunk having a hinged cover, bottom corner bumpers and a cover corner bumper, said bumpers being provided each with a recess, an angle bar adapted to fit around the corner of the trunk to engage the drawers when in closed position and at its ends engaging at the recesses in said bumpers, a knuckle on the top of the locking bar adapted to fit over the top of the trunk and beneath the lid and a hinge securing the bar to the trunk comprising leaf sections, one rigidly secured to the bar and one to the 100 trunk, said sections being relatively movable affording vertical adjustment for the locking bar.

9. In a bureau trunk, a locking bar embracing an angle bar adapted to be engaged 105 in locking position around the corner of the trunk with its lower end in a recess in a corner bumper, the upper end of said locking bar being provided with a flange to fit between the body and cover of the trunk.

10. A trunk of the class described comprising a body portion having a plurality of drawers slideable in the front thereof, a hinged cover thereon, provided with a lock, a locking bar, a bottom knuckle one at each front 115 corner of the trunk, each affording an upwardly opening recess in its top, corresponding recessed knuckles on the cover of the trunk affording a seat for the end of the locking bar and a flange on the upper end of the 120 locking bar adapted to fit beneath the lid.

In testimony whereof I have hereunto subscribed my name in the presence of two subscribing witnesses.

JAMES C. LYNCH.
